Inventor:

James Bolan,
By his attorney,
Charles S. Gooding.

UNITED STATES PATENT OFFICE.

JAMES BOLAN, OF BOSTON, MASSACHUSETTS.

TWO-PART PISTON FOR INTERNAL-COMBUSTION ENGINES.

Application filed February 23, 1922. Serial No. 538,451.

To all whom it may concern:

Be it known that I, JAMES BOLAN, a citizen of the United States, residing at Boston, in the county of Suffolk and State of Massachusetts, have invented new and useful Improvements in Two-Part Pistons for Internal-Combustion Engines, of which the following is a specification.

This invention relates to an improved two-part piston for internal combustion engines.

The device of this invention relates particularly to pistons for internal combustion engines with removable cylinder heads, and is adapted for use for any kind or make of internal combustion engine of the four cycle type.

The object of the invention is to make a two-part piston for internal combustion engines of light weight as free as possible from friction, of strong and simple construction and comparatively inexpensive to manufacture.

Another object of the invention is to overcome piston slap or knock and to prevent oil working up past the piston rings forming carbon in the piston rings and in the combustion chamber.

Another object of the invention is to provide a piston in two parts whereby the piston head, including the piston rings, can be easily removed from the engine without removing the connecting rod from the crank shaft and replacing the same for the purpose of cleaning out carbon or for adjustment of parts and replacing of worn parts. In internal combustion engines carbon is liable to form in the compression chamber and gather on the compression rings, and the under side of the piston head and in order to secure the greatest efficiency it is very desirable that the engine should be free from carbon. Internal combustion engines having a piston in one piece connected to the connecting rod render it necessary in order to remove the carbon that the oil should be drained from the oil pan, the oil pan taken off, the connecting rod disconnected from the crank and the connecting rod and piston pushed up through the top of the cylinder.

This is a very difficult operation, involves a large amount of labor and loss of time and all of these difficulties are overcome by the device of this invention.

In order to secure these different results, the piston of this invention is made of two principal parts, a head portion preferably of aluminum to secure lightness and carrying the compression rings, and a body portion of iron, the same as the cylinder walls, containing a wrist pin and bearings for the connecting rod. The body portion is connected to the head portion by two endless spiral springs. The member to which the springs are connected constitute a holder and forms, in effect, a portion of the piston head with which it has screw-threaded engagement.

The endless spiral springs referred to are connected to the said holder and at their lower portions partly encircle a pair of oppositely disposed hubs or bearings through which the wrist pin for the connecting rod extends. These springs have a constant tension at all times so that when the head is screwed on to the holder or spring carrier by rotating the same and locked thereto by means of a key, the two parts are held securely together.

An arched bridge extends over the connecting rod from one of said hubs to the other and between the head and the bridge which forms a part of the body portion there is interposed a steel ball movable between two or more steel discs. This ball constitutes a universal pivot against which the head portion bears and through which thrust from the explosion of the gases is transmitted directly to the body portion of the piston. There is a space between the head portion and the body portion of the piston so that the head portion is free to rock in any direction, being universally pivotally mounted through said ball on the body portion. By means of this construction it is evident that the head portion will not receive any side motion or thrust from the body portion.

Often the compression in a cylinder becomes too weak or too strong and by my im-

proved construction it is possible to regulate the compression by changing the distance of the head portion from the body portion and thus changing the amount of space in 5 the compression chamber where the explosion takes place. This result is accomplished by changing the size of the ball or by changing the thickness of the discs against which the ball bears, thereby reducing or increasing 10 the compression space in the top of the cylinder.

It will be seen that the head portion being of aluminum and the body portion of iron the extra relative expansion of the 15 aluminum part will have no effect on the body portion.

Although the oil tempered springs hereinbefore referred to are located at some distance from the heat of the piston head, 20 still spiral springs of various forms could be placed lower and connected to the spring holder or piston head and body portion without departing from the spirit of my invention. In the drawings no oiling system 25 as used is shown, but it is understood that the usual oiling system of devices of this character will be utilized.

To these ends the invention consists in the improved two-part piston for internal 30 combustion engines having, in combination, a body portion and a head portion connected together and constructed as herein-after set forth in the specification and particularly as pointed out in the claims.

35 Referring to the drawings:

Figure 1 is a side elevation of a two-part piston embodying my invention, a portion of a connecting rod being shown in connection therewith and broken away.

40 Fig. 2 is a sectional elevation taken on the line 2—2 of Fig. 1.

Fig. 3 is a sectional elevation taken on the line 3—3 of Fig. 2.

Fig. 4 is a sectional elevation similar to 45 Fig. 3 but with the piston head disconnected from the body portion thereof and with the body portion shown in connection with a portion of its cylinder.

Fig. 5 is a top plan of the body portion 50 of the piston.

Like numerals refer to like parts throughout the several views of the drawings.

In the drawings, 5 is the cylinder in which is located a piston 6 consisting of a body 55 portion 7 and a head portion 8. The head portion is provided with annular grooves 9 in which piston rings 10 are located. The body portion forms a loose fit in the cylinder 5 in the usual manner, while the rings 60 10 form a close fit therein. The body portion is provided with a pair of oppositely disposed inwardly extending hubs 11. The inner ends of the hubs 11 are connected together by a bridge 13 which extends over 65 the upper end of a connecting rod 14 which

is secured by a cap 15 and screws 16 to a piston pin 17. The head portion 8 has a bushing 18 therein which is interiorly screw-threaded to receive a shank 19 formed upon a holder 20. The holder 20 has two 70 oppositely disposed arms 21 and 22 which extend over and beyond the bridge 13 and terminate in hooks 23 and 24. These hooks receive and position a pair of oppositely disposed endless springs 25 and 26. The 75 lower part of each spring extends partly around a hub 11 and said springs are prevented from lateral movement toward each other by projections 27 and 28 formed on the lower side of the hubs 11. 80

Interposed between the holder 20 and the bridge 13 which forms a part of the body portion 7 is a ball 29 which is located in a recess 30 formed in the under side of the holder 20 and bears on its upper side 85 against a disc 31 located in the recess 30 and at its lower side said ball bears against another disc 32 located in a circular recess 33 formed in the top of the bridge 13. By this construction it will be seen that the head portion is connected to the body portion by the springs 25 and 26 and that said head portion is universally pivotally mounted upon the body portion by means of the ball 29. The ball 29 is concentric with the median longitudinal line of the piston so that thrust upon the head of the piston is transmitted directly to the center of the body portion through the ball 29. The upper portion of the shank 19 is slotted at 90 34 to receive a locking key 35 which locks the head portion 8 to the holder 20 when the parts are in operative position. 100

The general operation of the piston hereinbefore specifically described is as follows:—Assuming the parts to be in the relative positions illustrated in Fig. 4, the connecting rod 14 is connected to the pin 17 by means of the cap 15 and by the screws 16 as illustrated in Fig. 2. The piston head 8 is then lowered down toward the body portion 7 and the shank 19 enters the bushing 18 whereupon the piston head is rotated by means of a screw driver or other means inserted in a slot 36 in the top of said head 115 until the parts assume the relative positions illustrated in Fig. 2, whereupon the head is locked to the holder 20 by a key 35 which is driven into the slot 34 and into the slot 36 in the head 8. To remove the piston head portion from the cylinder and to disconnect it from the body portion 7, the reverse of the operation just described is performed. It is evident that the entire piston may be removed from the cylinder if desired. 120

In operation the body portion 7 of the piston is moved upwardly and downwardly with the connecting rod 18 and wrist pin 17 in the usual manner. It will be evident that all lateral thrust upon the piston as a whole 135

will be taken by the body portion 7 and that practically no lateral thrust will be imparted to the head portion 8.

When the piston head and body are driven 5 downwardly by the explosion of the compressed gas in the cylinder 5, the body portion 7 of the piston is forced downwardly, and through the ball 29 and the piston pin 17 a downward motion is imparted to the 10 piston rod 14 whereby the crank shaft is rotated in the usual manner. During the intake stroke however, the head portion 8 is drawn upwardly and carries the body portion with it by means of the springs 25 and 15 26, thus during the upward movement of the piston as a whole, the two parts thereof are held together against the suction of the intake by the springs 25 and 26.

In the operation of the piston of my invention any slight variation or lateral movement of the body portion, due to the thrust thereon of the connecting rod 14 will not be transmitted to the piston head 8 for the reason that said piston head is connected to 25 the body portion by the springs 25 and 26 and through the ball 29 and therefore the piston head is pivotally mounted on the body portion 7 so that it can rock in any direction, that is, it is universally pivotally 30 mounted on the body portion 7.

It will be evident that from the two-part construction of the piston hereinbefore described, and the particular manner in which the piston head is connected to the piston body by the springs 25 and 26 and the head being mounted on the body portion in such a manner as to be universally pivotally mounted thereon so as to tip in any direction, that any wear on the walls of the cylinder due to lateral thrust will take place 40 only throughout the extent of that portion of the cylinder with which the body portion of the piston comes in contact, but that portion of the cylinder with which the head only 45 comes in contact will not be worn by the head as there is no lateral thrust on it, therefore the compression will at all times be practically perfect.

It will also be evident that if it is desired 50 to obtain greater compression of the gas in the compression space in the cylinder it may be accomplished by inserting a larger ball to take the place of the ball 29 or if it is desired to have less compression, a smaller ball 55 may be inserted to take the place of the ball 29. The same results may be obtained by changing the discs 31 and 32 and placing thicker or thinner discs in their place to increase or diminish respectively the compression in the compression space of the cylinder.

I claim:

1. A piston for internal combustion engines having, in combination, a body portion and a head portion and pivotal means

concentric and in alignment with the median longitudinal line of said piston whereby said head portion is universally pivotally mounted on said body portion.

2. A piston for internal combustion engines having, in combination, a body portion and a head portion and pivotal means concentric and in alignment with the median longitudinal line of said piston whereby said head portion is universally pivotally 70 mounted on said body portion and means other than said pivotal means connecting said head portion to said body portion.

3. A piston for internal combustion engines having, in combination, a body portion and a head portion and pivotal means concentric and in alignment with the median longitudinal line of said piston whereby said head portion is universally pivotally mounted 75 on said body portion and means other than said pivotal means detachably connecting said head portion to said body portion.

4. A piston for internal combustion engines having, in combination, a body portion and a head portion and pivotal means concentric and in alignment with the median longitudinal line of said piston whereby said head portion is universally pivotally mounted 80 on said body portion and means other than said pivotal means yieldingly connecting said head portion to said body portion.

5. A piston for internal combustion engines having, in combination, a body portion and a head portion, a ball interposed between said body and head portion and concentric with the median longitudinal line of said piston whereby said head portion is universally pivotally mounted upon said body portion and means connecting said head portion to said body portion.

6. A piston for internal combustion engines having, in combination, a body portion and a head portion, a holder detachably fastened to said head portion and constituting a portion thereof and a ball interposed between said holder and said body portion concentrically positioned with the median longitudinal line of said piston whereby said head portion is universally pivotally mounted 100 on said body portion.

7. A piston for internal combustion engines having, in combination, a body portion and a head portion, pivotal means concentric and in alignment with the median longitudinal line of said piston whereby said head portion is universally pivotally mounted upon said body portion and springs connecting said head portion to said body portion.

8. A piston for internal combustion engines having, in combination, a body portion and a head portion and pivotal means concentric with the median longitudinal line of said piston whereby said head portion is universally pivotally mounted on said body portion.

- portion and a pair of oppositely disposed endless springs connecting said head portion to said body portion.
9. A piston for internal combustion engines having, in combination, a body portion and a head portion, a ball interposed between said body portion and head portion and positioned concentric with the median longitudinal line of said piston whereby said head portion is universally pivotally mounted upon said body portion, a holder detachably fastened to said head portion and constituting a portion thereof and springs connecting said holder to said body portion.
15. 10. A piston for internal combustion engines having, in combination, a body portion and a head portion, a holder detachably fastened to said head portion and constituting a portion thereof, and a ball interposed between said holder and said body portion and concentric with the median longitudinal line of said piston whereby said head portion is universally pivotally mounted on said body portion.
25. 11. A piston for internal combustion engines having, in combination, a body portion and a head portion, a holder detachably fastened to said head portion and constituting a portion thereof, a ball interposed between said holder and said body portion and concentric with the median longitudinal line of said piston whereby said head portion is universally pivotally mounted on said body portion and a pair of oppositely disposed endless springs connecting said holder to said body portion.
12. A piston for internal combustion engines having, in combination, a body portion and a head portion, a holder detachably fastened to said head portion and constituting a portion thereof, a ball interposed between said holder and said body portion and concentric with the median longitudinal line of said piston, a bearing member in said holder and a bearing member in said body portion, said bearing members being adapted to bear against diametrically opposite sides of said ball and yielding means connecting said holder to said body portion whereby said head portion is universally pivotally mounted on said body portion.
55. 13. A piston for internal combustion engines having, in combination, a body portion and a head portion, hubs extending transversely of said body portion, pivotal means concentric with the median longitudinal line of said piston whereby said head portion is universally pivotally mounted on said body portion and a pair of oppositely disposed springs engaging said head portion and transversely extending hubs, a piston pin extending through said transversely extending hubs and across said body portion and a connecting rod connected to said piston pin.
60. 14. A piston for internal combustion engines having, in combination, a body portion and a head portion, a holder detachably fastened to said head portion and constituting a portion thereof, a key locking said holder to said head portion and pivotal means concentric and aligning with the median longitudinal line of said piston, whereby said head portion is universally pivotally mounted on said body portion and detachable therefrom.
75. 15. A piston for internal combustion engines having, in combination, a body portion and a head portion, a ball interposed between said body portion and head portion and positioned concentric with the median longitudinal line of said piston whereby said head portion is universally pivotally mounted upon said body portion and a disc interposed between said ball and one of the other of said parts and constituting means for changing the distance of the head from the body portion whereby the compression space in the cylinder may be changed.
80. 16. A piston for internal combustion engines having, in combination, a body portion and a head portion, a ball interposed between said body portion and head portion and positioned concentric with the median longitudinal line of said piston whereby said head portion is universally pivotally mounted upon said body portion, a disc interposed between said ball and one of the other of said parts and constituting means for changing the distance of the head from the body portion whereby the compression space in the cylinder may be changed and springs connecting said head portion to said body portion.
85. 17. A piston for internal combustion engines having, in combination, a body portion and a head portion and pivotal means concentric and in alignment with the median longitudinal line of said piston whereby said head portion is universally pivotally mounted on said body portion, a piston pin extending across said body portion, a connecting rod engaging said piston pin, a cap engaging said piston pin and means to clamp said cap and connecting rod to said piston pin, said clamping means being adapted to be manipulated from the front or explosion end of the body portion of said piston to clamp said cap and connecting rod to said piston pin or to unclamp said cap and connecting rod from said piston pin.
100. 18. A piston for internal combustion engines having, in combination, a body portion and a head portion and pivotal means concentric and in alignment with the median longitudinal line of said piston whereby said head portion is universally pivotally mounted on said body portion, a piston pin extending across said body portion, a connecting rod engaging said piston pin and means to connect said connecting rod to said piston pin.

rod to said piston pin, said connecting means being adapted to be manipulated from the front or explosion end of the body portion of said piston to connect said connecting rod to said piston pin or to disconnect said connecting rod from said piston pin.

In testimony whereof I have hereunto set my hand in presence of two subscribing witnesses.

JAMES BOLAN.
